UNITED STATES PATENT OFFICE.

LOUIS N. STEIN, OF ROCHESTER, NEW YORK.

SLEEVE-HEAD.

SPECIFICATION forming part of Letters Patent No. 734,198, dated July 21, 1903.

Application filed April 9, 1903. Serial No. 151,885. (No model.)

To all whom it may concern:

Be it known that I, LOUIS N. STEIN, a citizen of the United States of America, and a resident of North St. Paul street, Rochester, New York, have invented certain new and useful Improvements in Sleeve-Heads, of which the following is a specification.

My invention relates to a sleeve-head which is designed for use conjointly with a shoulder-pad and is intended to be inserted in the upper end of a coat-sleeve, so as to build the shoulder of the wearer to a greater width and prevent the sleeve from hanging too abruptly from a projecting shoulder-pad.

15 Referring to the drawings, Figure 1 is a plan view of my sleeve-head, and Fig. 2 is an edge view of the same. Fig. 3 is an edge view of pad when finished viewed from the straight edge.

20 Referring to Figs. 1 and 2, 1 and 2 are two layers of wadding of similar shape, made of any desired form or character and superimposed upon each other. 3 is a line of stitching by which the two pieces of wadding are 25 sewed together, said line being located at a uniform distance from the curved edge. After being stitched together the two pieces of wadding are turned inside out, as shown in Fig. 3, and another line of stitching 4 is sewed 30 through the two layers inside of the inside

edge of the turned hem, so as to produce upon the curved edge of the pad a thickened rolled portion 6. A pad is thus formed which may be applied to the shoulder of a coat, placing the thickened edge of the pad so that it will 35 project beyond the shoulder into the upper curved portion of the sleeve and will support the sleeve of the coat so as to fill out the shoulder in a desired manner. The structure is therefore called a "sleeve-head" or 40 "filling."

Having thus described my invention, what I claim as new, and desire to secure by Letters Patent, is—

As a new article of manufacture, a sleeve- 45 head, substantially crescent-shaped, composed of several layers of material stitched together by a line of stitches parallel to its semicircular edge, then turned inside out and stitched together by a second line of stitches 50 parallel to the first line so as to produce a thickened semicircular edge, substantially as described.

Signed by me at Rochester, New York, this 4th day of April, 1903.

LOUIS N. STEIN.
